DIAPER

Norman L. Seltzer, Newton, Mass., assignor to The Kendall Company, Walpole, Mass., a corporation of Massachusetts

Filed Oct. 7, 1958, Ser. No. 765,797

11 Claims. (Cl. 139—383)

This invention relates to single-layer open-weave bird's-eye diapers having a reduced tendency to ravel at cut edges. By a single-layer diaper I mean a fabric with one set of warp and filling yarns, as distinguished from the well known gauze diaper which is woven with two plies or layers joined by an interweave.

Such single-layer diapers, woven with the familiar bird's-eye or similar fancy weave, are popular and widely used diapers in commerce. Due to the weave pattern employed, wherein certain yarns "float" over yarns in the opposite set without intersecting at each crossing, the fabric has an appealing softness and absorbency, particularly suited to the characteristics required in a satisfactory diaper. At the same time, such a fabric is durable in use, and is also economical to weave.

All single-layer bird's-eye diapers with which I am familiar, however, suffer from one serious disadvantage. The very factors of design that make for softness and absorbency in this structure also make the fabric very susceptible to ravelling or fray at the edges where individual diapers have been cut from the original roll of cloth. This ravelling is particularly marked when such a cut piece of fabric is laundered. In order to produce a satisfactory launderable diaper from such single-layer bird's-eye fabrics, it is the universal practice to protect the cut edges in some manner. Commonly, this is done by hemming, although attempts have been made to protect the cut edge by impregnating it with latex or some liquid binder material.

Neither hemming nor impregnation, however, are entirely satisfactory solutions to the problem. Not only do these practices appreciably increase production costs, but they also make the diapers uncomfortable, since impregnated edges are more stiff and unyielding than the body of the fabric, and hemmed edges are bulky, heavy, retain soil and stains, and are slow drying.

A satisfactory diaper, besides being absorbent and inexpensive to manufacture, should be soft and yielding over its entire area. It should also be substantially ravel-free at its edges even after repeated washings.

One object of the invention is to produce an inexpensive single-layer diaper having reduced tendency to ravel at its edges without the necessity for impregnating, stitching, fusing, or hemming the edges.

Another object of the invention is to provide a single-layer diaper that is soft and yielding over its entire area.

A further object of the invention is to make a diaper having the advantages of the popular single-layer bird's-eye construction without the ravelling problem ordinarily associated with such fabrics.

The above objects of the invention will be more fully apparent from the following detailed description when read in conjunction with the accompanying drawings, in which:

Fig. 1 is a plan view of a diaper made in accordance with my invention.

Fig. 2 shows, in draft form, a portion of the diaper of

2

Fig. 1 having adjacent bird's-eye and plain-weave structures, and

Fig. 3 shows one repeat of another bird's-eye-weave pattern, also in draft form.

5 In Figures 2 and 3 the warp yarns run vertically in the drawings; and the filling yarns, horizontally. The x's indicate where the warp yarns pass over the filling yarns.

I have now discovered that by combining two different 10 weaves in a diaper the advantages of a single-layer bird's-eye weave may be had without the problem of raveling edges ordinarily associated with bird's-eye. Thus, plain-weave bar portions are woven adjacent the conventional bird's-eye-weave body portion of a single-layer diaper, 15 and the diapers are pinked in the bar portion. If the number of filling yarns per inch in the plain-weave pinking bar portions is increased, the bar portions will have even greater ravel-resistance when pinked, even though not otherwise protected.

20 As shown in the figures, the preferred diaper is woven from warp yarns 14 and filling yarns 16, forming a single-layer bird's-eye body portion 22, selvage edges 24 and 26, and plain weave pinking bar portions 28 and 30. The pinking bar portions 28 and 30 have been pinked to 25 give pinked edges 32 and 34. Normally, but not necessarily, the diaper is woven with its longer dimension running across the loom; in this case the pinking bars run in the direction of the filling yarns 16. As can be seen, all of the warp yarns 14 are used in the weaving of the 30 single-layer body portion 22 and are also used in the weaving of the bar portions 28 and 30.

As mentioned above, Figs. 2 and 3 show in draft form weave constructions that may be used in making the diaper of this invention. Fig. 2 shows portions of the 35 plain weave pinking bar 28 (similar to pinking bar 30) and bird's-eye weave body portion 22. Fig. 3 gives the pattern of an alternative bird's-eye weave for the body portion 22.

The principal difference between the bird's-eye-weave 40 structures of Fig. 2 and Fig. 3 is the size of the pattern. The pattern of Fig. 2 has eight warp and eight filling yarns in each repeat; that of Fig. 3 has only six of each. As used in this specification and the claims, "bird's-eye" and "bird's-eye weave" mean not only the customary diamond weave patterns often referred to as "bird's-eye," such as the "bird's-eye" weaves of Figs. 2 and 3, but also all other fancy weaves in which an effect other than that of a plain weave is obtained by weaving.

The diapers of the invention are preferably woven with 45 from about 56 to about 124 warp yarns per inch in both the body and the pinking bar portions and from about 21 to about 50 filling yarns per inch in the body portion. When the bar runs in the filling direction, between 50 and 70 picks per inch in the pinking bar are preferred, 55 though the use of a plain weave without additional picks, or a plain weave together with any number of additional picks per inch, even as few as ten, will tend to reduce ravelling. This increase in the pick count may be effected by an ordinary "pinch-pick" mechanism, if desired. Preferably, the pinking bar is not impregnated with any type of binder material.

The yarn sizes may range from about 10/1 to about 60 40/1 in both the warp and the filling, although yarn sizes between 16/1 and 31.5/1 are generally preferred. The twist multiples of the yarns may be as low as 3.00 and as high as 4.75, twist multiples between 3.80 and 4.00 being preferred. Such yarns are best made from staple cotton, rayon, or other water-swellable fibers or mixtures thereof. Filamentary yarns, particularly those made of nonwater-swellable material such as nylon, generally will not give 65 the same ravel-resistance in the fabric constructions customarily used for diapers.

I claim:

1. A soft, absorbent diaper with ravel-resisting edges, said diaper being made of warp yarns and a single set of filling yarns interwoven to form a single-layer bird's-eye weave body portion, two selvage edges, and two plain weave bar portions, said yarns being cellulosic and water-swellable, said bar portions running in the direction of said filling yarns along opposing edges of said body portion, all of said warp yarns of said body portion and of said selvage edges being interwoven in said bar portions, said bar portions having a greater number of filling yarns per inch than said body portion, and said bar portions being pinked along their outermost edges.

2. A diaper with ravel-resisting edges, made of warp yarns and a single set of filling yarns interwoven to form a single-layer bird's-eye weave body portion and at least one plain weave pinking bar portion, said yarns being cellulosic and water-swellable, said bar portion running in the direction of said filling yarns along an edge of said body portion, and said bar portion having a greater number of filling yarns per inch than said body portion.

3. A diaper with ravel-resisting edges, made of warp yarns and a single set of filling yarns interwoven to form a single-layer bird's-eye weave body portion and at least one plain weave pinking bar portion, said yarns being cellulosic and water-swellable, said bar portion running in direction of said filling yarns and having a greater number of filling yarns per inch than said body portion, and said bar portion being pinked along its outermost edge.

4. A diaper with ravel-resisting edges, made of warp yarns and a single set of filling yarns interwoven to form a single-layer bird's-eye weave body portion and at least one plain weave pinking bar portion, yarns being cellulosic and water-swellable, said bar portion running in the direction of said filling yarns along an edge of said body portion, said bar portion having at least about 50 filling yarns per inch.

5. A diaper with ravel-resisting edges, made of warp yarns and a single set of filling yarns interwoven to form a single-layer bird's-eye weave body portion and two plain weave pinking bar portions, said yarns being cellulosic and water-swellable, said bar portions running in the direction of said filling yarns along opposing edges of said body portion, and said bar portions having at least 70 filling yarns per inch.

6. A rectangular diaper with ravel-resisting edges, made of warp yarns and a single set of filling yarns made of staple, cellulosic, water-swellable fibers, said yarns being interwoven to form a single-layer bird's-eye weave body portion having opposing selvage edges and two opposing cut edges, the fabric of said diaper along at least one of said cut edges being a plain weave pinking bar portion, said bar portion running in the direction of said filling yarns along an edge of said body portion, said bar portion being pinked along its outer edge.

7. A woven diaper made of cellulosic, water-swellable yarns comprising at least one ravel-resisting single-layer strip running in the filling direction of said fabric and having a pinked longitudinal edge, an absorbent panel joined to the opposite longitudinal edge of said strip, said

panel comprising a single-layer of bird's-eye diaper fabric woven integral with said single-layer strip, said single-layer strip being of plain weave and being substantially free of impregnants, said single-layer strip and said single-layer of bird's-eye diaper fabric being woven from a single set of filling yarns.

8. A rectangular diaper with ravel-resisting edges, woven from warp yarns and a single set of filling yarns, comprising, a piece of single-layer fabric having two opposite cut edges and being bounded on the two other opposite sides by a woven selvage, the yarns in a narrow zone along each of said cut edges being woven in a plain weave and being free of bonding media, hemming, and stitching, substantially all of the remaining yarns in said fabric being woven in a bird's-eye weave, the number of yarns per inch in said zones which run lengthwise of said zones being greater than the number of yarns per inch of the corresponding yarns in the remainder of said fabric said cut edges being pinked.

9. A rectangular diaper with ravel-resisting edges, woven from warp yarns and a single set of filling yarns, comprising, a piece of single-layer fabric having two opposite cut edges and being bounded on the two other opposite sides by a woven selvage, the yarns in a narrow zone along each of said cut edges being woven in a plain weave and being free of bonding media, hemming, and stitching, substantially all of the remaining yarns in said fabric being woven in a bird's-eye weave, and said cut edges being pinked.

10. A single ply diaper with ravel-resisting edges made of warp yarns and a single set of filling yarns comprising a bird's-eye woven body portion with two plain woven fillingwise bar portions having pinked edges, said bar portions being woven integral with and along fillingwise edges of said body portion, and said bar portions having a greater number of filling yarns per inch than said body portion.

11. A rectangular woven diaper with ravel-resisting edges, made from cellulosic water-swellable yarns having a single-layer body portion with two opposing selvage edges and two opposing cut edges, the fabric of said diaper along at least one of said cut edges being a single-layer bar portion and being pinked, said body portion being of bird's-eye weave construction and said bar portion being of a plain weave construction, said bird's-eye and plain weave constructions being woven from a single set of filling yarns.
